(57) CLAIM

The ornamental design for a writing device, as shown and described.

DESCRIPTION

1. Writing device

1.1 : Perspective

1.2 : Front

1.3 : Left

1.4 : Top

1.5 : Bottom

A new, original, and ornamental design for a writing device; of which the following is a specification, reference being made to the accompanying drawings, forming a part hereof. The broken lines illustrate portions of the writing device that form no part of the claimed design.
